(57) **CLAIM**

The ornamental design for a beverage tablet contact plate for a beverage machine, as shown and described.

DESCRIPTION

FIG. 1 is a top, front, perspective view of a beverage tablet contact plate for a beverage machine;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The short dash-long dash broken lines illustrate boundaries of the claimed design and form no part of the claimed design. The dash-dash broken lines illustrate portions of the beverage tablet contact plate for a beverage machine that form no part of the claimed design.
